UNITED STATES PATENT OFFICE.

DAVID W. DODSON, OF WICHITA, KANSAS.

WALL CONSTRUCTION.

1,370,686.

Specification of Letters Patent.

Patented Mar. 8, 1921.

Application filed April 14, 1919. Serial No. 289,884.

To all whom it may concern:

Be it known that I, DAVID W. DODSON, a citizen of the United States, residing at Wichita, in the county of Sedgwick and State of Kansas, have invented certain new and useful Improvements in Wall Constructions; and I do declare the following to be a full, clear, and exact description of the invention, such as will enable others skilled in the art to which it appertains to make and use the same.

This invention relates to wall constructions, and it relates more specifically to an improved sectional reinforced wall of concrete blocks.

One object of this invention is to provide an improved wall formed in sections each of which is adjustable, for tightening the joints, independently of the other sections.

20 A further object is to provide an improved sectional wall in which any section can be repaired or reconstructed independently of the other sections.

Other objects and advantages may become 25 apparent to persons who read the following details of description in connection with the accompanying drawings, in which:—

Figure 1 is a side elevation illustrating a sufficient portion of my improved wall to 30 illustrate the invention.

Fig. 2 is a horizontal sectional view of the structure shown in Fig. 1, the section being taken along the line 2—2 of Fig. 1.

Fig. 3 is a perspective view showing the 35 detail construction of the blocks and their relation to one another and the binding and adjusting rods or bolts.

Fig. 4 is an enlarged vertical sectional view, the section being taken along the line 40 4—4 of Fig. 1.

Fig. 5 is a perspective view more clearly illustrating the connection of the rods or bolts with one of the posts or upright channel beams, the building blocks being indicated in broken lines.

Fig. 6 is a perspective view illustrating the relation of the bolts or rods to the channel-beam which is disposed at a corner where two walls meet at right angles to one 50 another, the building blocks being indicated in broken lines.

Fig. 7 is a perspective view showing a means of splicing two channel-beams when it is desired to extend the wall to an unusual 55 height.

Referring to these drawings in detail, in

which similar reference characters correspond with similar parts throughout the several views, my improved wall consists broadly in combining a plurality of beams 60 10, a plurality of bolts 11, and a plurality of building blocks 12, in the relation disclosed by the drawings and hereinafter described more specifically.

The beams 10 may be of the channel-beam 65 construction as shown, or they may be of any appropriate and well known construction in which parallel spaced flanges are provided.

These beams are arranged in upright position, and may be either vertical and arranged in a straight row, or they may be otherwise arranged according to the formation of the wall of which they constitute elements. 75

The bolts 11 are of ordinary construction, each consisting of a threaded end having a nut thereon, and these bolts extend through grooves 13 in the respective building blocks 12, and through holes 14 in the flanges of 80 the respective beams 10. By referring to Figs. 2, 3, 4 and 5, it will be seen that the rods 11 are arranged in pairs and that the holes 14 through which they extend are arranged in a plane which intersects the beam 85 laterally, and that the distance between the pairs of bolts is equal to the distance between the pairs of grooves 13 near the upper and lower ends of each block 12.

The blocks 12 are each formed with 90 tongues or ridges 15 and with grooves 15', the latter being of a size and shape to receive the tongues. Moreover, each block 12 is formed with diagonal upper and lower ends so that when the blocks are arranged in 95 vertical and horizontal rows, as shown in Fig. 1, each block of one horizontal row overlaps vertical portions of blocks of the two contiguous vertical rows. Moreover, when the blocks are thus arranged in the 100 wall, the upper pairs of grooves in one horizontal row register with the lower pairs of grooves in the superposed horizontal row. It will be seen, therefore, that this arrangement of the grooves 13 provides a continuous groove or channel from one to another of the beams 10, so that each pair of bolts 11 engages with two horizontal rows of the blocks. 105

In further considering Figs. 1 and 2 of 110 the drawings, it will be seen that my improved wall comprises separately and inde-

pendently adjustable and separately and independently reconstructable sections, each section consisting of two half beams 10, two or more pairs of rods 11 and one or more horizontal rows of blocks 12. In using the term half-beams, it is to be understood that one flange and half of the web of each beam 10 belongs to one of said sections, and that the other flange and other half of the web belongs to another one of said sections. In thus considering the structure, let it be assumed that one of the blocks 12 is found defective or becomes damaged so that it needs to be replaced. For instance, consider the block through which the line 4—4 passes as being defective:—In this instance, it would only be necessary to loosen the nuts on the superadjacent bolts of this section, bend these bolts laterally out of groove 13, force this block (and those above it in the same vertical row) upward until it is removed from the wall, then replace this block with a new one by a downward movement between the contiguous vertical rows of blocks, replace the other blocks of the same vertical row and then replace the bolts 11 and tighten the other nuts.

In the event that the joints between the vertical rows become leaky from weather conditions, temperature or natural shrinkage, the nuts on the bolts can be tightened so as to draw the blocks more firmly together and close such leaky joints. It will be seen that such adjustment or removal and replacement of the nuts can quickly and easily be effected, because they are easily accessible in the space between the flanges of the beam.

Referring to Fig. 6, it will be seen that when it is desired to form a corner or partition in a building structure, the middle portion of the channel beam may be apertured at 16 to receive a pair or pairs of bolts 11.

Referring to Fig. 7, it will be seen that this wall may be extended to any reasonable height by placing two of the channel beams 10 in alinement and employing splicing

plates 10' which are bolted or riveted to the meeting ends of the beams.

Although I have described this invention very specifically, it is not intended to limit the same to these exact details of construction and arrangement of parts, but I am entitled to make appropriate changes within the scope of the inventive idea disclosed in the foregoing description and following claims.

What I claim as my invention is:—

1. A wall section comprising two flanges of different upright channel-beams, two adjusting bolts each extending through each of these flanges, a row of building blocks seated between said flanges of this section and having upper end portions fitted between said bolts, and a row of building blocks fitted between these flanges and having their lower ends seated on the first said row and between said bolts, said building blocks being provided with tongue-and-groove joints therebetween, said upper and lower end portions being provided with alined grooves in which said bolts are seated.

2. A wall section comprising two flanges of different upright channel-beams, two adjusting bolts each extending through each of these flanges, a row of building blocks seated between said flanges of this section and having upper end portions fitted between said bolts, and a row of building blocks fitted between these flanges and having their lower ends seated on the first said row and between said bolts, said building blocks being provided with tongue-and-groove joints therebetween, said upper and lower end portions being provided with alined grooves in which said bolts are seated, each of said upper ends and lower ends being formed with a horizontal surface and an inclined surface, said inclined surface being at an angle to said grooves.

In testimony whereof I have hereunto set my hand.

DAVID W. DODSON.
